Primary Examiner — Deanna L Pratt(74) Attorney, Agent, or Firm — Mitchell Law PLLC;
Matthew W. Mitchell(57) **CLAIM**

The ornamental design for an inflatable chair, as shown.

DESCRIPTION

FIG. 1 is a front isometric view of the inflatable chair of the present invention;

FIG. 2 is a back isometric view of the invention of FIG. 1; FIG. 3 is a front view of the invention of FIG. 1;

FIG. 4 is a rear view of the invention of FIG. 1;

FIG. 5 is a side view of the invention of FIG. 1, as seen from the left side of FIG. 3;

FIG. 6 is a side view of the invention of FIG. 1, as seen from the right side of FIG. 3; and,

FIG. 7 is a top plan view of the invention of FIG. 1.

1 Claim, 7 Drawing Sheets(56)
